UNITED STATES PATENT OFFICE.

ALBION K. WASHBURN, OF BRIDGEWATER, MASSACHUSETTS.

SOLE-LEVELING MACHINE.

SPECIFICATION forming part of Letters Patent No. 435,882, dated September 2, 1890.

Application filed January 30, 1890. Serial No. 338,680. (No model.)

To all whom it may concern:

Be it known that I, ALBION K. WASHBURN, of Bridgewater, in the county of Plymouth and State of Massachusetts, have invented 5 certain new and useful Improvements in Sole-Leveling Machines, of which the following, taken in connection with the accompanying drawings, is a specification.

The object of my invention is to so improve 10 the construction of boot and shoe sole leveling machines that the work can be done much better and with less labor than with any machine now in use. This object I attain by the mechanism shown in the accompanying 15 drawings, in which—

Figure 1 is a side elevation of my invention. Fig. 2 shows in elevation a part of the jack. Fig. 3 is a plan of my machine. Fig. 4 is a detail in section. Fig. 5 is a front elevation of my machine. Fig. 6 is a view, partly 20 in vertical section, showing parts of the jack.

In the drawings, A represents the frame of the machine, upon which, in suitable housings, the main shaft B is mounted. This shaft 25 B is driven by means of the pulley B'. An eccentric (indicated by dotted lines at B² in Fig. 1) is hung upon the main shaft B. The eccentric B², acting through an eccentric-strap B³ and rod B⁴, gives motion to the bent 30 lever B⁷, to which it is connected by a pivot-pin B⁵, which is adjustable in the slot B⁶. The bent lever B⁷ is pivoted to a part of the frame of the machine at B⁸. The function of the bent lever B⁷ is to give a forth and back motion to the leveling-roller B¹², to which it is connected by means of the rod B¹⁰ and forked piece B¹¹. (See Fig. 3.)

To admit of the roller B¹² having a rocking motion as well as a forth and back and 40 an up and down one, I have the following-described device: E, Figs. 1 and 4, is a short cylinder mounted upon trunnions E', which are journaled in the standards A'. Outside the short oscillating cylinder E, I have a second cylinder C, which is free to rotate, although it has no longitudinal motion in relation to the cylinder C, and has arms C² C² extending horizontally from it. These arms C² C² terminate in slideway-pieces C⁴ C⁴, in 45 which the journal-boxes of the roller B¹² slide. From the above it may be seen that the entire frame-work in which the roller B¹²

is hung is free to be swung up and down and to be turned on its longitudinal axis, and that the roller itself may, by the action of 55 the rod B¹⁰, Fig. 3, be caused to move back and forth. The amount of motion given to the roller B¹² is determined by the position of the clamping-pivot B⁵ in the slot B⁶ of the bent lever B⁷, Fig. 1.

C⁶ is a handle, by means of which the position of the roller B¹² may to some extent be determined by the operator. The foot-lever D⁴, pivoted at D⁵, is connected to the roller-frame by means of the rod D², spring-coupling D', rods D D, and cross-bridge C³, and serves to force the roller B¹² down onto the sole of the boot or shoe being worked upon. 60

The device by which the shoe is held while subject to the action of the machine consists 70 of a swinging jack, the base of which I have designated by the letter J. This base is pivoted to the frame of the machine by journals J', and is connected by a standard J², Figs. 1 and 5, (having a rack-gear J³ at its 75 upper end,) to a pinion J⁴, made on the end of the shaft W' of the hand-wheel W. The shaft W' is indicated by dotted lines in Fig. 5, and is held in place by a standard and quill A² A², attached to the frame of the machine, so that by turning the hand-wheel W the jack may be swung forth and back, as 80 may be desired.

That part of the jack that is used for supporting the heel part of the boot or shoe consists of a standard H, which has pivoted at its top a short pin-lever H², said pin-lever having a last-pin H³ of the usual construction and arrangement.

The pin-lever is swung forth and back and 90 held in place by the following-described device: H⁴ is a link pivoted to the pin-lever at H⁵ and passing downward into the base of the standard H, as shown more clearly in Fig. 6, the lower end resting upon a spiral 95 or other suitable spring H⁸, the tendency of the spring H⁸ being to force the link H⁴ upward, and acting through the pin-lever H² to throw the upper end of the last-pin H³ backward and release the last. H⁶ is a lever 100 pivoted to the standard H at H⁷. One end of this lever passes through a slot h made in the link H⁴, while the other end is connected to a swiveling screw-nut H⁹ by a pivot-bolt H¹².

A screw H^{10} , having a hand-wheel H^{11} at its top, passes through the swiveling nut H^9 , and having a step at H^{13} serves to operate the lever H^6 , and through it the link H^4 and last-pin H^8 . Thus the operator by turning the hand-wheel H^{11} one way or the other can cause the last-pin to swing in either direction, the spring H^8 serving as a retractor.

That part of the jack that acts as a toe-support and guide consists of an upright G G' , pivoted to the base of the jack at G^2 , Fig.

1. This upright has a swiveling screw-nut at G^3 , through which a screw-rod G^4 passes. The screw-rod G^4 is connected by a swivel-joint G^5 to the standard H , so that by turning the hand-wheel G^6 the upright G G' may be moved toward or away from the heel-support, and as the guide or guard G^7 , as well as the toe-support, is attached to the upright G G' , they must of necessity move also.

The upright G G' is made in two parts, as indicated in Figs. 1 and 2, the parts G and G' being so made that they can be adjusted one upon the other and held firmly in place by clamping-bolts b or by any suitable means.

Near the upper part of the upright G G' , I have a bracket-piece T' , which supports a toe-piece T . This toe-piece T is adjusted by the hand-screw T^2 .

30 To operate my machine, the user places the boot or shoe on the jack in the usual manner, adjusting the toe-piece T and the guard G^7 so that the work may be done to the best advantage. Now the machine may be set in

motion—that is, the roller B^{12} may roll back and forth over the surface of the sole to be leveled. The pressure on the sole may be graded by means of the foot-lever D^4 . By turning the hand-wheel W the entire jack, taking with it the boot or shoe, may be so placed that the roller may operate on any desired part of the shoe, or the jack may be brought so far forward that the roller will not touch the sole at all, but traverse on the guard G^7 .

45 I claim—

1. In a sole-leveling machine, the combination of the eccentric B^3 , eccentric-strap B^8 , and rod B^4 , being adjustably connected to the bent lever B^7 , with the bent lever B^7 , rod B^{10} , 50 and roller B^{12} , substantially as and for the purpose set forth.

2. In a sole-leveling machine, the combination of the roller B^{12} with the adjustable guard G^7 and hand-wheel W , said guard being adapted to be thrown over by the hand-wheel W into such a position as to receive the roller B^{12} and support it when desired, substantially as and for the purpose set forth.

55 In testimony whereof I have signed my name to this specification, in the presence of two subscribing witnesses, on this 24th day of January, A. D. 1890.

ALBION K. WASHBURN.
